UNITED STATES PATENT OFFICE.

SAMUEL GROSSMAN, OF NEW YORK, N. Y.

STAIR.

No. 888,882.

Specification of Letters Patent.

Patented May 26, 1908.

Application filed June 6, 1907. Serial No. 377,512.

To all whom it may concern:

Be it known that I, SAMUEL GROSSMAN, a citizen of the United States, residing in the borough of Manhattan, New York city, county and State of New York, have invented certain new and useful Improvements in Stairs, of which the following is such a full, clear, and exact description as will enable any one skilled in the art to which it appertains to make and use the same, reference being had to the accompanying drawings, forming part of this specification.

My invention relates to improvements in metal stairs in which the upper surface of the tread is provided with a layer or slab of composition material such, for instance, as concrete, asphalt or cement, and the principal objects of the invention are to provide a neat composite structure of this kind which while substantially made and possessing great strength is of a light weight, and also in which the composition material of the tread is completely protected at its forward edge by a substantial portion of the metal structure itself.

With these and other objects in view, my invention consists in the various novel and peculiar arrangements and combinations of the several different parts of the device, all as hereinafter fully described and then pointed out in the claims.

I have illustrated types of my invention in the accompanying drawings, wherein:—Figure 1 is a vertical longitudinal sectional view of stairs made in accordance with my invention. Fig. 2 is a similar view of stairs showing a modification of the invention.

In the accompanying drawings, wherein like numbers of reference designate like parts throughout, 1 indicates an ordinary stair stringer made preferably of metal and to the inner side of which are secured a series of separate angle-iron brackets 2 which are secured to the stringer by means of rivets 3. These brackets 2 are right angle shaped pieces with the vertical part thereof adapted to receive the riser and the horizontal part thereof adapted to receive the next adjacent tread above such riser, so that each of the separate angle-iron brackets serves as a support for the riser and the next adjacent tread above the same.

Each riser 4 comprises a piece of sheet metal, preferably rolled sheet steel, cut to size and formed at its lower end with a rearwardly extending bend 5 which forms a sufficiently deep and wide groove or channel 6 for receiving therein the rear end of the tread, below the riser, as well as a substantial quantity of the composition material 8. The lower and bent end 9 of each riser, is carried well forward and somewhat forward of the plane of the front face of the riser itself, so as to provide a substantial flange at such point, and the rear end of the tread 7, is secured to such flange by means of a bolt and nut 10, as shown in the drawings, the nut lying upon the upper face of the tread 7, and within the groove or channel 6. The upper end of each riser 4 is provided with a rearwardly extending flange 11, which is bolted by means of a nut and bolt 12, to the underside of the tread 7 next above the riser, and which tread rests throughout its width upon the upper flange of such riser. The nut of the bolt 12 lies upon the upper surface of the tread 7, and is, like the nut of the other bolt, at the rear, embedded in the mass of composition material, 8. The upper flange 11 of the riser is in the same plane with the horizontal flange of the angle-iron 2, so that the tread 7 rests flatly upon the respective flanges of these two parts.

In Fig. 1, the tread 7 is carried forwardly of the riser 4, next below it, and is provided with a downward bend 13 and is thence carried upwardly and backwardly in a horizontal direction where it terminates in a flange 14. This bend provides, on its exterior, a shoulder 15, into which the corner or angle 90 at the upper end of the tread fits, as shown in the drawing. Upon the interior, this bend provides a comparatively deep groove or channel 16 into which the plastic material 8 extends, while the flange 14 thereof provides 95 practically a countersunk place 17 for the plastic material, which being likewise held at the rear end in the groove 6 of the riser 4, is thus securely retained in its position after it is once placed therein and becomes hardened 100 or set. In inserting the composition 8, which is done when it is in plastic condition, the same is filled into the recess, which is provided upon the upper surface of the tread

by means of the bent up part 13 and 14 at the forward end, and this material is filled in such manner that its upper surface is flush with the metallic flange 14, at the forward 5 end of the tread. In this way the sheet metal of the riser 7 being thus carried forwardly and upwardly constitutes the forward edge or nose of the composite edge and, of course, protects the less durable composition 8, at a point where it would necessarily be subjected to hard usage. When once the 10 composition 8, which may be of any suitable well-known material, such as cement, asphalt or concrete or the like, and is inserted in plastic condition, becomes hard, it forms a 15 permanent part of the stair structure and it is so securely retained in place at its front and rear edge that it is impossible for it to work loose or become dislodged. Furthermore, 20 the joint made at the rear of the composition material 8 and the riser 4 is a very close one which practically seals the structure at that point and prevents the working in of any foreign material.

In Fig. 2, the forward end of the tread 18 is modified by being unbent and flat, while the upper end of the riser 19 is modified by being bent forwardly, upwardly and rearwardly at 20, 21, and 22, to provide the same 25 sort of metallic edge or nose, as shown in Fig. 1, both for the purpose of protecting the forward edge of the composition 8, as well as providing a deep recess in the upper surface of the tread for receiving such composition. 30 In this structure, the forward end of the tread 18 is bolted, by means of a nut and bolt 23, to the forward bend 20 of the riser 19, which bend 20 is flush with the horizontal flange of the angle-iron bracket 2, and the 35 bolt of the nut 23 lies within the recess in which the plastic material is filled. In other respects the structure is similar to that described in reference to Fig. 1.

An important advantage in the manner of 40 constructing the recessed tread and of inserting or placing therein the composition material forming the upper surface thereof is that such composition is easily filled in and may be made in a very thick body which will 45 last a very long time, and the manner of retaining the composition in place holds it securely by both its front and rear edge, so as to prevent any liability of working loose, it being undercut at both of such edges. In 50 the construction shown in Fig. 1, the metallic tread 7 has the forward extension 55 13, 14, which is bent upwardly and thence back upon itself, formed integral with the tread and this has certain advantages in regard to strength. In this construction there 60 is an absence of any rivet heads upon the underside of the tread, thereby presenting a smoother and neater appearance.

Having thus described my invention what I claim and desire to secure by Letters Pat- 65 ent is:

1. Stairs having suitably supported separate metal risers and treads, the riser having its upper end flanged and fastened to the adjacent tread above, and having its lower end 70 provided with a groove or recess for receiving the rear end of the next adjacent tread and also the body of material on said tread, and a body of material placed upon said tread.

2. Stairs having suitably supported separate metal risers and treads, the riser having its upper end flanged and fastened to the adjacent tread above, and having its lower end 75 provided with a groove or recess for receiving the rear end of the next adjacent tread and 80 also the body of material on said tread, a rearwardly opening recess or groove at the forward end of said tread also adapted to receive the body of material, and a body of material placed upon said tread. 85

3. Stairs having suitably supported separate metal risers and treads, the tread having its forward end provided with a recess for receiving and holding a body of material, the adjacent riser being provided at its lower 90 edge with a recess for the body of material, and a body of material on said tread.

4. Stairs having suitably supported separate metal risers and treads, the tread having its forward end provided with a recess for receiving and holding a body of material, the adjacent riser being provided at its lower 95 edge with a recess or groove extending backwardly beyond the plane of the body of the riser for receiving the rear end of the adjacent tread and the body of material, and a body of material on said tread. 100

5. Stairs having suitably supported separate metal risers and treads, the tread having its forward end provided with a recess for receiving and holding a body of material, the adjacent riser being provided at its lower edge with a rearwardly extending recess or groove, the rear end of the adjacent tread lying within said recess or groove on the riser 110 and being fastened thereto, and the upper end of the riser being fastened to the adjacent tread, and a body of material on said tread. 115

6. Stairs having suitably supported separate metal risers and treads, the tread having its forward end provided with a recess for receiving and holding a body of material, the adjacent riser being provided at its lower edge with a rearwardly extending recess or 120 groove, the rear end of the adjacent tread lying within said recess or groove on the riser and being fastened thereto, and the upper end of the riser being provided with a flange fastened to the adjacent tread, and a body of 125 material on said tread.

7. Stairs having suitably supported separate metal risers and treads, each tread having its forward end bent over upon itself and constituting the forward edge of the tread and providing a recess for receiving and holding plastic material, and each riser being likewise bent at its lower edge for receiving the plastic material.

In testimony whereof, I have hereunto set my hand in the presence of the two subscribing witnesses.

SAMUEL GROSSMAN.
